UNITED STATES PATENT OFFICE.

JAMES T. DOUGINE, OF CHICAGO, ILLINOIS.

EXCAVATING-MACHINE.

SPECIFICATION forming part of Letters Patent No. 307,751, dated November 11, 1884.

Application filed April 16, 1884. (No model.)

To all whom it may concern:

Be it known that I, JAMES T. DOUGINE, a citizen of the United States, residing in Chicago, in the county of Cook and State of Illinois, have invented a new and useful Improvement 5 in Excavating-Machines, of which the following is a specification.

This invention relates to digging or excavating machines wherein an endless belt or 10 chain of buckets is employed to elevate the dirt, and more particularly to improvements upon the machine heretofore patented to me in Letters Patent of the United States No. 225,001, under date of March 2, 1880.

15 My present invention consists, in connection with the elevator, which is provided with an advance rotary cutter driven from the lower pulley-shaft of the elevator-chain, either by sprocket-wheels and chains, gears, or other 20 suitable mechanism, of a casing or covering, preferably made of sheet metal, inclosing said driving mechanism, for the purpose of protecting it from the dirt.

The invention also consists in providing the 25 shaft of this rotary cutter with revolving knives or clearers on each end of the shaft outside of this casing which incloses the driving gear or mechanism, so as to clear a way for the casing and prevent the same offering obstructions to the advance of the machine or to its 30 lateral motion when the elevator is swung from side to side.

The invention also consists in providing this 35 advance cutter and the lower end of the elevator with a sliding hood or shield, which may be shot forward into the embankment, for the purpose of shielding or protecting the advance cutter and elevator-chain from a caving embankment, which contingency frequently occurs.

In my former patent, referred to above, I mounted the engine or means for driving the elevator-chain in or upon the swiveling frame which carries the upper end of the elevator 45 and its driving-pulley, so that the engine and its connecting mechanism will always bear the same relation to the driving-shaft of the elevator-chain as the elevator swings from side to side; but in the present improvement I effect 50 this result in a different way; and herein also my invention consists—that is to say, in

making the lower pivot of the swiveling frame in the form of a hollow sleeve, which fits in a suitable sleeve or journal in the cross-beam of the frame, and then communicating power to 55 the driving-shaft of the elevator-chain by means of a shaft extending up through this hollow pivot or journal of the swiveling frame, so that the engine or source of power may be located or mounted upon the stationary platform of the carriage, boat, or other vehicle upon which the machine is mounted.

The invention also consists in mounting the inner end of the delivery or discharge elevator in a similar swiveling frame and communicating power to the driving shaft or pulleys of this discharge-elevator by gearing, or connecting the central vertical shaft, which extends up through the sleeve or hollow pivot of the swiveling frame of the discharge-elevator, with 70 the similar vertical shaft which extends up through the sleeve or hollow pivot of the other swiveling frame.

The invention also consists in the novel devices and novel combinations of devices here- 75 in shown and described.

In the accompanying drawings, which form a part of this specification, and in which similar letters of reference indicate like parts, Figure 1 is a side elevation of an excavating-machine embodying my invention. Fig. 2 is an enlarged cross-section showing the swiveling frame in elevation. Fig. 3 is a detail plan view of the advance rotary cutter, the casing being sectioned on one side to show the driving mechanism; and Fig. 4 is an enlarged elevation of section of the chain and buckets.

In said drawings, A represents the platform of the vehicle A', upon which the apparatus is mounted. A² are the vertical standards or 90 frame-pieces upon which the swiveling frame B is mounted, and D is the frame of the elevator, upon which are journaled the shafts d¹ d² of the sprocket-wheels d³ d⁴, which carry the elevator-chain and buckets D'. This frame 95 D is supported at its upper end in the swiveling frame B, the shaft d¹ being also journaled in the swiveling frame B. The lower end of the elevator-frame D is provided with a cross-frame or legs, D², having wheels d⁴, which rest 100 and run upon a curved track, E, on the front end of the platform A. The lower end of the

elevator-frame is swung around on this track E by means of the windlass E' and rope E², connected to the cross-frame D².

For a fuller description of this track and 5 windlass, as well as the guiding or steering mechanism F F', and the mechanism G G', for propelling the vehicle forward, I would refer to my previous patent, above mentioned, as these devices constitute no part of the present invention.

The swiveling frame B, which supports the upper end of the elevator, is provided at its lower end with a hollow pivot or sleeve, b, which rests and is supported in a suitable journal or sleeve, b', on the bridge-piece B', which extends across between the vertical standards or frame-pieces A²; and the upper end of this swiveling frame B is provided with a pivot or short shaft, b², which is journaled in the 15 bridge-piece B², which extends between the vertical frame-pieces A² at the top thereof. The shaft d carries the upper sprocket-wheels, d² d³, and is provided with a bevel-gear, b³, which meshes with the bevel-gear b' on a shaft, 20 b⁵, which is journaled in suitable bearings, b⁶, secured to the swiveling frame B; and this shaft b⁵ is provided near its lower extremity with a spur-gear, b⁷, which meshes with a spur-gear, b⁸, on the shaft b⁹, that extends up 25 through the bridge-piece B', and through the hollow sleeve b on the end of the swiveling frame B. Power is communicated to this shaft b⁹ from an engine or other suitable power located on the platform of the machine by 30 means of a bevel-gear, b¹⁰, on the counter-shaft b¹¹, which bevel-gear meshes with a bevel-gear, b¹², on the vertical shaft b⁹. The counter-shaft b¹¹ is of course provided with a belt-pulley or other means for connecting it with 35 the source of power.

H is the discharge-elevator. Its outer end may preferably be supported on a track similar to that which supports the front end of the elevator D, and its inner end is mounted 45 in a swiveling frame in every way similar to the swiveling frame B of the elevator D, and its sprocket-wheel shaft h is driven by means of a bevel-gear, h', on said shaft, meshing 50 with the bevel-gear h² on the vertical shaft h³, which is provided at its lower end with a spur-gear, h⁴, which meshes with a spur-gear, h⁵, on the shaft b⁹, so that the elevator H, or its endless chain H', is driven in this way directly from the driving mechanisms of the elevator D. The upper or discharge end of the 55 excavating-elevator D is mounted in or about the axial or pivotal line of its swiveling frame B, and the inner or receiving end of the discharge-elevator H is likewise mounted in or 60 about the axial or pivotal line of its swiveling frame, so that the swinging of said elevators from side to side will not interfere with the proper registering of said elevators with each other or with the hopper interposed between them.

A³ represents a cross-brace extending be-

tween the pairs of vertical frame-pieces A² at the top, and a a' represent brace-rods for said frame.

The elevator-frame pieces D are provided at 70 their front ends with horizontal extensions I, on the ends of which the advance rotary cutter K is mounted. This rotary cutter K is provided with one or more rows of curved digging-teeth, k, and it is driven from the lower 75 sprocket-wheel shaft, d', by means of a sprocket-wheel, k', on said shaft d', and a chain, k², and sprocket-wheel k³ on the shaft k⁴ of the rotary cutter and digger. These sprocket-wheels k' and k³ and chain k² are inclosed in a sheet-metal or other casing, L, which serves to protect them from dirt. Of course it will be understood that other means of communicating power from the shaft d' to the rotary cutter may be employed. The shaft k⁴ of the rotary cutter extends out on each side through these casings L, and bears on each end one or more revolving knives or clearers, K', which serve to cut away the embankment as the elevator is swung laterally from side to side, and which 80 also serve to clear the way for the casing and frame-pieces at each end of the rotary cutter.

M represents a sliding shield, consisting, preferably, of a flat sheet or plate of metal, and mounted in suitable guides or ways on the 95 frame-pieces M', so that it can be slid forward so as to project over the rotary cutter and the end of the elevator-chain for the purpose of protecting the same from a tumbling embankment, as occasion may require. To project 100 this shield forward I connect it by a rod, m, with a lever, m', pivoted to the elevator-frame, the handle of which projects down near the windlass E', in convenient reach of the operator.

The elevator-chain and its buckets may preferably consist of a number of overlapping plates, c, on the links of the chain, every third or fourth one of said plates having a back curved up, as shown at c', and one or two vacant links being left between each series of plates, as shown at c''.

O is a jack-screw, one of which is provided at each corner of the platform.

P is a brace-rod for the elevator H, connected at its upper end to a cross-arm secured to an extension of the upper pivot of the swiveling frame B of said elevator, so as to permit the elevator to turn with the swiveling frame. One of these brace-rods is attached to each 120 side of the elevator-frame H.

I claim—

1. In an excavating-machine, the combination of the elevator having its frame D provided with horizontal extensions I I, with an 125 advance rotary cutter or disintegrator, and casings L, inclosing the driving mechanism of said rotary cutter, substantially as specified.

2. The combination, with the elevator of an excavating-machine, of an advance rotary 130 cutter driven from the lower pulley-shaft of the elevator by sprocket-wheels and chains or

equivalent mechanism, and the casing inclosing said sprocket-wheels and chains, substantially as specified.

3. The combination, in an excavating-machine, of an elevator, an advance rotary cutter, and a sliding shield to protect the same against falling embankments, substantially as specified.

4. In an excavating-machine, the combination, with the elevator, of a sliding shield, M, mounted on the digging end of said elevator, substantially as specified.

5. The combination, in an excavating-machine, of the elevator with a swiveling frame, B, in which the upper end of said elevator is mounted, said swiveling frame being provided with a hollow sleeve journaled in the bridge or cross-frame piece, and a driving-shaft extending up through said hollow sleeve, connected with the driving-shaft of the elevator in said swiveling frame, and communicating with the source of power, substantially as specified.

6. The combination, with the swinging excavating-elevator D, having its upper end mounted in a swiveling frame, B, and in the axial line of said frame, of a swinging discharge-elevator, H, having its inner end mounted in a similar swiveling frame and in the axial line thereof, substantially as specified.

7. In an excavating-machine, the combina-

tion of the elevator, the swiveling frame B, the driving-shaft d, journaled in said swiveling frame, bevel-gear b³ thereon, shaft b⁵, provided with bevel-gear b⁴ and spur-gear b⁶, and shaft b⁹, provided with spur-gear b⁸, extending through the hollow sleeve b of said swiveling frame, and bevel-gear b¹², meshing with bevel-gear b¹⁰ on the counter-shaft b¹¹, substantially as specified.

8. The combination, with the elevator D, of swiveling frame B, provided with hollow sleeve b, journaled in the bridge-piece, the shaft b⁹, extending up through said hollow sleeve to communicate power to said elevator D, and provided with a spur-gear, h⁵, meshing with a spur-gear, h⁴, on the shaft h³, and the discharge-elevator H, mounted in a similar swiveling frame at its upper end, and driven by the shaft h³, substantially as specified.

9. The combination, with the elevator of an excavating-machine, of an advance rotary cutter, driving mechanism for operating said rotary cutter from the lower pulley-shaft of said elevators, a casing inclosing said driving mechanism, and revolving clearers or knives at each extremity of said rotary cutter outside of said casing, substantially as specified.
